DISPENSER CABINET

Archie S. Krueger, Norman J. Slye, and Bernard E. Blanchard, all of Green Bay, Wis., assignors to Alwin Manufacturing Company, Green Bay, Wis., a corporation of Wisconsin

Filed Feb. 23, 1965, Ser. No. 83,937

Term of patent 14 years

(Cl. D52—2)

FIG. 1 is a view in front three-quarter perspective showing a dispenser cabinet embodying our new design.

FIG. 2 is a rear three-quarter perspective view thereof.

FIG. 3 is an end elevational view thereof with an end wall partly broken away to expose the interior in transverse section.

We claim:

The ornamental design for a dispenser cabinet, as shown.
